UNITED STATES PATENT OFFICE.

ERNEST CHAPIN COLE, OF CHICAGO, ILLINOIS.

STOVE.

1,278,859.

Specification of Letters Patent. Patented Sept. 17, 1918.

Application filed July 17, 1914. Serial No. 851,541.

To all whom it may concern:

Be it known that I, ERNEST CHAPIN COLE, a citizen of the United States, and a resident of Chicago, in the county of Cook and State of Illinois, have made an Improvement 5 in Stoves, of which the following is a specification.

My invention is in the class of sheet-metal stoves employed for heating rooms or apartments. The body of the stove is made in halves, or in two practically duplicate parts, the same being tapered from the horizontal middle upward and downward so that when detached from each other they are adapted 10 to be nested for storage or transportation.

The invention further includes an improvement in which a casting conceals and protects the screw-bolt fastening by which the meeting ends of the body parts are enclosed and held together when the stove is set up for use.

The details of construction, arrangement, and combination of parts are as hereinafter described, and illustrated in the accompanying drawing, in which,

Figure 1 is an end view of the stove, one of the upper corners being broken away to show interior form or construction.

Fig. 2 is mainly a side view of the stove, 30 the front portion being cut away and shown in section.

Fig. 3 is an enlarged horizontal section on the line 3—3 of Fig. 2.

Fig. 4 is an enlarged vertical section on 35 the line 4—4 of Fig. 1.

In Figs. 1 and 2, A and A' indicate, respectively, the upper and lower halves or practically duplicate portions of the stove body. These parts are struck up by dies 40 from sheet metal of suitable thickness, and they are tapered from the horizontal center or middle portion upward and downward, so that they may be conveniently nested. As shown in Figs. 2 and 4, the parts A and A' 45 are outturned at their meeting edges, thus forming curved flanges a and a'.

For the purpose of securing the parts A, A', together, that is to say, for confining and covering the flanges a, and a', I employ a sheet-metal band B which is semi-circular 50 in cross section and made of such width that it is adapted, as shown in Figs. 2 and 4, to embrace the flanges a, and a'. The ends of this band B are provided with laterally pro-

jecting metal pieces constituting parallel 55 flanges b, and a screw-bolt C is inserted through the said flanges, and when the nut is turned up it is obvious that the band B will be drawn tightly around the flanges a, a' of the stove body, so that they will be 60 pressed together and thus form a tight joint. Exterioly, the band forms also an ornamental attachment or portion of the stove as a whole.

In order to conceal and protect the bolt- 65 fastening C and the flanges b of the band B, the casting D is provided with a vertical extension d which, as shown in several figures of the drawing, extends upward and is concaved on its inner side to adapt it to in- 70 close or cover the bolt-fastening and contiguous parts. The casting D may be secured to the body part A' by means of screw-bolts, which permit convenient detachment when it is desired to separate the parts 75 A, A', from each other for the purpose of nesting them, etc. I thus produce a stove body which is distinguished by lightness, cheapness, facility of separation of its main parts, and is also highly ornamental in ap- 80pearance.

I have shown in Figs. 1 and 2 the parts A, A', as provided with vertical corrugations which impart strength and rigidity as well as conduce to ornamental appearance.

The upper part A of the stove is provided with a stove-pipe collar a² and cover a³ for the hole through which fuel is introduced.

It will be understood that, in practice, legs will be provided for supporting the stove 90 in the usual way.

What I claim is:—

The herein described improved stove comprising upper and lower separable duplicate stove-body members, the upper member having a continuous ledge projecting outwardly therefrom at its lower end, a vertical flange extending upwardly from the outer edge of said ledge, the lower stove-body member having a continuous ledge projecting outwardly from its upper end, and a vertical flange extending downwardly from the outer edge of such ledge, the ledges of the respective members juxtaposed against each other with the respective vertical flanges project- 95 ing in opposite directions, an expansible split metal band having a semi-circular cross section inclosing the ledges with its 100 105

inner face engaging the free edges of the oppositely projecting flanges, the ends of the split band having outwardly extending portions, means engaging said end portions for drawing same together, the inner edges of the band engaging the outer face of the upper and lower members, a draft door casting secured to the lower member, and a

curved extension projecting upwardly from said casting and inclosing the split ends of 10 the curved band and its end fastening means.

ERNEST CHAPIN COLE.
